FLIER BLOCK BRAKE

Wilson Woodrow Tew, Elon College, N. C.

Application July 25, 1939, Serial No. 286,464

2 Claims. (Cl. 57—116)

My invention relates to flier block brakes for the fliers of spinner bobbins.

The invention is designed as an improvement over the flier block brake of my U. S. Letters 5 Patent No. 2,144,903, dated January 24, 1939, the particular object in view being to provide a simplified, inexpensive, brake of the quick-acting pure friction type.

Other, and subordinate objects are also comprehended by the present invention, all of which, together with the exact nature of my improvement, will be readily understood when the succeeding description and claims are read with reference to the drawing accompanying and forming 10 part of this specification.

In said drawing:

Figure 1 is a view in side elevation of a spinner bobbin and flier block embodying my improvements.

20 Figure 2 is a fragmentary view in vertical section taken on the line 2—2 of Figure 1 looking in the directions of the arrows and drawn to an enlarged scale.

Figure 3 is a view in top plan drawn to an 25 enlarged scale.

Figure 4 is a view in bottom plan of the friction brake member and lug together with the housing for said brake member, and

30 Figure 5 is a view in bottom plan of the friction brake member detached.

Referring to the drawing by numerals, I have shown therein my improved flier block brake as embodied in a spinner bobbin 1 and flier block 2 of the type featured in my aforesaid patent, the bobbin having an axial bore 3 by means of which it is frictionally fitted on the usual upwardly tapering spindle 4 for rotation thereby. Flier block 2 comprises a sleeve-like hub 5 surmounting the bobbin 1 and freely rotatable on the spindle 4, an intermediate base flange 6 on said sleeve, a laterally extending lug 7 on the lower end of the sleeve, and thread-guiding arms 8 terminating in guide eyes 9 and supported by a mounting 10 on said hub for rotation therewith.

45 According to the instant invention, the upper end of the bobbin 1 has countersunk therein, concentrically thereof, a circular, open bottom housing 11 of shallow cup-like form having a pressed fit in said bobbin 1 and provided in the top 13 thereof with an axial aperture 12 fitting loosely around the hub 5 of block 2, said housing enclosing the lug 7, and the top 13 of the housing supporting the flange 6 of the hub 5. The aperture 12, it will be understood, is of a diameter 50 such that the lug 7 may be inserted therethrough

by tilting the hub 5, prior to mounting the bobbin and flier block on the spindle 4.

The housing 11 has fitted therein a friction brake member comprising a diametrically split, thin band 14 of resilient metal reacting against the side wall of the housing 11 to frictionally grip the same and having a pair of inwardly extending, laterally spaced, terminal arms 15 extending upon opposite sides of the lug 7, respectively, and normally reacting against said sides to frictionally grip said lug therebetween. Preferably the arms 15 are provided with outwardly bowed, inner ends 16 curving in the arc of a circle eccentric to the axis of rotation of the lug 7 and normally clamping the lug between the same.

15 The operation of the described brake will be readily understood. Under rotation of the bobbin 1 the arms 15 are thrown outwardly by the action of centrifugal force, thereby releasing the lug 7, whereby the bobbin 1 is free to rotate relative to the flier block 2. When the bobbin 1 slows down below a predetermined speed, the arms 15 react against the sides of the lug 7 and brake the flier block 2 to a stop when the bobbin is stopped. The lug 7 being eccentric to the axis 20 of rotation, likewise the ends 16 of arms 15, the result is that the band 14 is intermittently tightened against the housing 11 under rotation of the flier block 2 and rotation thereof and the braking action of the arms 15 is applied with intermittently increasing force until the flier block is 25 stopped.

30 The foregoing will, it is believed, suffice to impart a clear understanding of my invention without further explanation.

35 Manifestly the invention, as described, is susceptible to modification without departing from the inventive concept and right is herein reserved to such modifications as fall within the scope of the subjoined claims.

40 What I claim is:

1. A brake for use between a spinner bobbin and a flier block, relatively rotatable about the axis of a common spindle, comprising a circular cup-like housing adapted to be countersunk in 45 fixed inverted position in the top of said bobbin concentrically of said axis, an axial sleeve adapted to extend from said block into said housing and having a radial lug thereon rotatable on said housing about said axis, and a band of flexible metal fitting in said housing, said band being diametrically split for reaction into frictional engagement with the inner circumferential wall of said housing and terminating in a pair of laterally spaced arms extending inwardly of the band 50 55

upon opposite sides of the sleeve, respectively, in the plane of rotation of said lug, said arms normally reacting toward said sleeve to frictionally engage opposite sides of said lug and 5 brake rotation thereof and being movable outwardly under rotation of said bobbin and the action of centrifugal force away from said sleeve out of braking position.

2. A brake for use between a spinner bobbin 10 and a flier block, relatively rotatable about the axis of a common spindle, comprising a circular cup-like housing adapted to be countersunk in fixed inverted position in the top of said bobbin concentrically of said axis, an axial sleeve adapted to extend from said block into said housing 15 and having a radial lug thereon rotatable on said housing about said axis, and a band of flexible

metal fitting in said housing, said band being diametrically split for reaction into frictional engagement with the inner circumferential wall of said housing and terminating in a pair of laterally spaced arms extending inwardly of the band upon opposite sides of the sleeve, respectively, in the plane of rotation of said lug, said arms normally reacting toward said sleeve to frictionally engage opposite sides of said lug and brake rotation thereof and being movable outwardly 10 under rotation of said bobbin and the action of centrifugal force away from said sleeve out of braking position, said arms having outwardly bowed terminal ends, respectively, eccentric to said axis for intermittently varying frictional engagement of the arms with said lug. 15

WILSON WOODROW TEW.
